UNITED STATES PATENT OFFICE.

ADAM KASPER, OF ECKLEY, PENNSYLVANIA

LANTERN

1,119,258.

Specification of Letters Patent

Patented Dec. 1, 1914.

Application filed July 3, 1914. Serial No. 846,775.

To all whom it may concern:

Be it known that I, ADAM KASPER, a citizen of the United States of America, residing at Eckley, in the county of Luzerne 5 and State of Pennsylvania, have invented certain new and useful Improvements in Lanterns, of which the following is a specification.

This invention relates to certain new and 10 useful improvements in lanterns.

An object of the invention is to provide a lantern in which the illuminated burner is inclosed in a glass casing so that liability of the light being blown out is obviated.

15 A further object of the present invention is to provide a lantern in which the burner is arranged within a glass casing with an adjustable screen arranged in the top wall in the form of a tubular member that may 20 be moved to a position within the casing when the lamp is out of use so that injury to the same is obviated, while the same may be readily extended to afford an entrance for air to provide for a perfect combustion.

25 With the above general objects in view and others that will appear as the nature of the invention is better understood, the same consists in the novel construction, combination and arrangement of parts to be 30 hereinafter more fully described and then claimed.

In the drawing forming a part of this application and to which reference is had herein by like characters designating corresponding parts throughout the several views:—Figure 1 is a vertical cross sectional view through the casing with the tubular screen projected. Fig. 2 is a top plan view of the same partly broken away, 40 and Fig. 3 is a detail perspective view of the tubular screen.

Briefly described, the invention consists of a lantern comprising corner stiles to receive glass walls cushioned at their bottoms on a base plate and removably secured at their upper edges to a cover. The illuminating burner is arranged within the casing and the air for combustion of the lamp enters through the upper wall of the casing and is controlled by a vertically adjustable tubular screen member that may be projected when the lamp is in use to provide a passage in the upper wall for the air and

to be received within the casing to provide a closure and be removed from the upper surface of the cover to prevent injury thereto.

Referring more in detail to the accompanying drawing, the reference numeral 10 designates the base of the lamp which may be of sheet metal or any other suitable material having arranged on the upper wall thereof channel recesses 11 for the glass side walls 12. These glass walls 12 are received in the channel recesses 11 on a cushioned member 11' while the vertical side edges of the glass are received in angle sockets 13 formed on the vertical corner stiles 14.

The corner stiles 14 support the cover wall 15 which may be either formed integral therewith or connected thereto in any suitable manner, there being provided a second wall 16 spaced above the cover wall 15 and carrying a pair of eyes to which are secured the ends of a bail handle 17. The upper walls 15 and 16 are provided with registering openings which receive the tubular screen member 18 closed at its upper end by a cap 19 and having secured to the lower peripheral edge thereof the tubular section 20 carrying an annular flange 21, the cap being provided with an outstanding flange to limit the downward movement of the screen, its upward movement being checked by the flange 21. The tubular screen member 18 is received in the openings of the cover walls and is limited in its upward movement as shown in Fig. 1 by the flange 21 engaging the cover wall 15. The second spaced cover wall 16 is provided with a pair of oppositely disposed sockets 22 to receive the pins 23 formed on opposite faces of the tubular section 20 and to provide a support for the said tubular section to hold the same in protruded position as shown in Fig. 1. When it is desired to collapse the tubular screen section 18 or cause the same to be received within the glass casing, the said tubular screen section is revolved until the pins 23 register with openings 24 in the upper walls 15 and 16 which will permit the tubular section to descend with the upper section 19 received on the upper wall 16 of the cover.

A hanger arm 25 is positioned centrally of the tubular screen section 18 and is connected at its upper end to the upper section

19 and is guided in its downward direction through the spider 26 carried by the tubular section 20 of the screen 18 and supports on its lower end a smoke bell 27 which is positioned centrally above the illuminating burner 28.

Should it be desired to remove the glass walls 12 from the side stiles and base channel recesses, for repair or collapsing of the 10 lamp, the spring pressed pins 29 carried by the upper walls 15 and 16 are retracted, in which position the upper ends of the glass walls may be moved inwardly. Entrances is gained into the casing through the door 30 15 which is hinged as at 31 to one of the side stiles 14 and carries at its swinging end a fastening member 32 of any suitable form that will hold the door in closed locked position.

20 It is believed that the operation of the lantern from the above description will be readily apparent and it is to be noted that when the lantern is in use the tubular screen member 18 is projected as shown in Fig. 1 to 25 provide for an entrance of air through the upper walls 15 and 16 for the purpose of combustion while the smoke bell 27 will in a manner reflect the light rays. When the lantern is out of use and to provide for a 30 minimum amount of space occupied by the same, the tubular screen section 18 is lowered into the glass casing in a manner as above described and as shown in dotted line position in Fig. 1.

35 While I have shown and described the preferred embodiment of my invention, I do not wish to confine myself to the exact details of construction shown, as various forms, modifications and arrangements of the 40 parts as shown may be had without depart-

ing from the spirit and scope of the invention as claimed.

I claim:

1. In a lantern, a transparent casing, a two part upper wall, a burner within the 45 casing, a tubular vertically movable and revoluble screen section mounted in the upper wall, means for limiting the upward and downward movement of the screen, and means for holding the screen locked against 50 downward movement.

2. In a lantern, a casing, an upper wall for the casing having an opening therein, a vertically movable and revoluble tubular screen mounted in the opening, means for 55 limiting the vertical movement of the screen in up and down directions, a smoke bell suspended from the tubular screen, means for holding the smoke bell centered relatively to the screen, and illuminating means within 60 the casing.

3. In a lantern, a casing having a two part upper wall provided with a central opening, the upper member of the wall being provided with oppositely aligned sockets and 65 with oppositely aligned openings, a tubular screen member arranged in the opening and provided with pins arranged to engage the sockets to hold the screen in elevated position, and to pass through the openings to 70 permit the screen to be depressed, illuminating means arranged in the casing and a smoke bell suspended from the screen.

In testimony whereof I affix my signature in presence of two witnesses.

ADAM KASPER.
